UNITED STATES PATENT OFFICE.

EDWARD J. ZIOCK, OF ROCKFORD, ILLINOIS.

SINGEING APPARATUS.

Original application filed May 7, 1924, Serial No. 711,565. Divided and this application filed September 20, 1924. Serial No. 738,754.

This invention relates to the finishing of knitted articles after they have been manufactured, that is, knitted and otherwise completed in so far as their fabric structure is concerned. By "finishing" I refer to operations and processes which follow the manufacturing operations and are performed in bleaching, mercerizing and dyeing, and may consist in wetting, developing, singeing, dyeing, drying and the like. By "knitted articles" I mean fabric articles, either knitted or woven, and especially hosiery. While the present invention is applicable to the finishing of various knitted articles by operations such as referred to, it is intended primarily for finishing stockings, especially those of high grade and texture which require a fine degree of finish.

The present application is a division of my application Serial No. 711,565, filed May 7, 1924, now Patent No. 1,623,080, and has more particular reference to singeing and to the provision of apparatus adapted not only for performing the operation of singeing but other finishing operations as well. Such other operations could be performed by the substitution of appropriate devices for the singeing elements used in the present apparatus as will be readily understood from a consideration of this and my parent application.

The primary purpose of the present invention is, therefore, to provide an improved method of and apparatus for singeing knitted articles and performing other finishing operations of a related character. The object is to perform these operations expeditiously and uniformly so as to promote economy in the cost of production and enable a uniform degree of finish in the resultant production.

Other objects and attendant advantages will be appreciated by those skilled in this art as the invention becomes better understood by reference to the following description when considered in connection with the accompanying drawings, in which:

Figure 1, is a diagrammatic view showing one embodiment of my invention;

Fig. 2, is an enlarged section taken on the line 2—2 of Fig. 1; and

Fig. 3, is a section taken substantially on the line 3—3 of Fig. 2.

My improved singeing or finishing device is preferably, but not necessarily, used in

connection with an endless carrier to which stocking or article-holding forms are attached at spaced intervals and which is adapted to be moved either continuously or intermittently for advancing the forms from station to station at which different finishing operations are performed or the stockings or other articles are placed upon and removed from the forms.

In the present case I have shown for purpose of illustration merely, an endless carrier designated generally by 5, comprising a pair of roller chains 6, trained over sprocket wheels 7 and 8, one of which may be a driver, and crossbars 9 connecting the roller links 11 of the chains at equally spaced intervals. The roller chains are supported and travel on suitable tracks 10. In this instance the carrier travels in a clockwise direction viewing Fig. 1, continuously and at a constant speed.

To these crossbars are attached the article-holding forms designated generally by 12, which may be of any suitable or preferred construction. Each form in the preferred embodiment of my invention is comparatively flat and shaped to conform to the contour of the stocking or other article so that when the latter is drawn on to the form the fabric will be held flat, preferably in a slightly stretched condition, so that it will be uniformly presented to the singeing or other finishing devices. Each form is preferably equipped with suitable means such as clamping members 13 described in my companion application Serial No. 738,756, filed September 20, 1924, for holding the stocking to a predetermined length on the form.

The singeing device comprises a pair of singeing elements, in the present instance a pair of vertical gas burners 14 or the equivalent and means for moving them back and forth in a quick singeing stroke in which the gas flames rapidly traverse both sides of a stocking during its travel and in a return stroke into operative relation to the next succeeding stocking for repeating the operation. The burners 14 are mounted on a carriage 15 which is supported by rollers 16 to travel back and forth on the upright flanges of the carrier tracks 10, a suitable guide 17 being in this case employed for preventing lateral displacement of the lower end of the burners. A gas supply hose 18 is attached

to said lower end, as shown in Fig. 2. The carriage has a pair of pawls 19 adapted to engage any connector bar 9 for movement therewith and to be released therefrom at a predetermined point by striking a stationary abutment 21. The burners normally occupy a position intermediate two adjoining stocking forms as shown in Fig. 3 with the pawls 19 engaging a crossbar 9 on the carrier, so that the burner carriage travels with the carrier to the left. During travel of the burner carriage the distance between centers of said two adjoining forms, a spring tension will be stored up in a coiled contractile spring 22 attached at 23 to a central part on the carriage 15 and at 24 to a fixed or stationary part, with the result that when the pawls 19 are released by contact against the abutment 21 at the end of said travel the spring will return the carriage in a rapid movement to a starting position at which the pawls will be engaged by the next succeeding connector bar 9. During this rapid stroke (to the right) the burners traverse the stocking in a movement opposite to the travel of the interposed stocking and singe any protruding fibres on the surface thereof. The rapid singeing stroke may be cushioned by any suitable means such as an air cylinder 25 which in the present case serves as a housing for the spring 22. This operation is repeated, automatically, by reason of the fact that the singeing carriage is moved on its forward stroke by the continuously moving form carrier and is returned on its working stroke by the spring pressure stored up during the forward stroke.

It will be observed that the gas burners 14 are shaped to conform to the major axis of the stocking form so that the forms may be arranged comparatively close together without interference with the burner and so that the flames will strike the front edge of a stocking substantially from end to end thereof at the same instant. While this is not essential, it is nevertheless, a factor in promoting uniformity in the singeing operation. When gas burners are used for singeing, the jets should deliver a uniform length flame from end to end of each burner.

It should be understood that the singeing device herein disclosed is for purpose of illustration merely, and that any suitable or preferred form of singeing element or other device for performing a finishing operation may be substituted for the burners 14. In other words, any of the different processing or finishing operations described in my parent application, might be performed by a device of the character disclosed and claimed herein. It will be manifest therefore, that my invention should not be confined to the particular construction herein disclosed, nor to the singeing of a single stocking at each working stroke, but is

adapted to considerable change and modification within the spirit and scope of the appended claims. In the claims by using the word "stocking" I mean any knitted or fabric article, by the words "stocking form" 70 I mean a form suitable for holding any such article, and by the words "singeing" and "singeing device" I mean any finishing operation and any device which may perform such operation substantially in the manner disclosed herein and within the purview of the present invention.

I claim as my invention:

1. In apparatus for finishing stockings, in combination, a traveling carrier, stocking forms spaced thereon, and a singeing device having a singeing element at each side of the stocking passage and mounted to travel in one direction in a singeing stroke across the forms and in the opposite direction in an idle stroke with the forms but disposed out of singeing relation thereto.

2. In apparatus for finishing stockings, in combination, a traveling carrier, stocking forms spaced thereon, and a singeing device having a singeing element at each side of the stocking passage and mounted to travel with the carrier between adjoining stocking forms for a given distance and in a rapid singeing stroke past a following stocking form.

3. Apparatus for finishing knitted articles comprising, in combination, a carrier means for actuating the same, a plurality of stocking forms connected at spaced intervals to the carrier to move therewith, a singeing device having spaced singeing elements between which the stocking forms are adapted to pass, and means for causing the singeing elements to move opposite in direction to the direction of travel of the carrier while the stockings are in motion for traversing the stockings in the singeing stroke.

4. Apparatus for finishing knitted articles comprising, in combination, a carrier, a plurality of stocking forms connected at spaced intervals to the carrier to move therewith, a singeing device having spaced singeing elements between which the stocking forms are adapted to pass, spring-operated means for moving the singeing device in one direction in a quick singeing stroke in which the singeing elements rapidly traverse both sides of a stocking and come into operative relation to a next succeeding stocking for repeating the singeing operation, and means for successively moving said singeing device with said carrier in a direction opposite to the singeing stroke whereby the spring is loaded for the singeing stroke.

5. Apparatus of the character described comprising, in combination, a track, a carrier mounted to travel thereon in a certain plane, a plurality of stocking forms attached to said carrier at spaced intervals, a singeing device having singeing elements in

- spaced relation between which the stocking forms are adapted to pass, said singeing device being movable back and forth in a plane parallel to the plane of travel of the stocking forms, and means for effecting said back and forth movement of the singeing device during travel of the form carrier, comprising a pawl for moving said device with the carrier in the idle stroke and spring means 5 for returning said device on the singeing stroke.
6. Apparatus of the character described comprising, in combination, a track, a carrier mounted to travel thereon in a certain 15 plane, a plurality of stocking forms attached to said carrier at spaced intervals, a singeing device having singeing elements in spaced relation between which the stocking forms are adapted to pass, said device being movable back and forth in a plane parallel to the plane of travel of the stocking forms, and means whereby in its back and forth motion the singeing device will be moved by and with the carrier a predetermined 20 distance in one direction and independent of said carrier a predetermined distance in the opposite direction whereby to traverse a stocking form in a singeing stroke.
- 25 7. Apparatus of the character described comprising, in combination, a track, a carrier mounted to travel on said track in a certain plane, a plurality of stocking forms attached in spaced intervals to said carrier, spaced singeing elements between which said stocking forms are adapted to be moved, said elements being shaped to conform generally to the major axis of the stockings and the forms therefor for the purpose mentioned, and a carriage for moving said singeing elements mounted to move back and forth in a plane parallel to the plane of travel of the form carrier.
- 30 8. Apparatus of the character described comprising, in combination, a track, a carrier mounted to travel on said track in a certain plane, a plurality of stocking forms attached in spaced intervals to said carrier, spaced singeing elements between which said stocking forms are adapted to be moved, and a carriage for moving said singeing elements mounted to move back and forth in a plane parallel to the plane of travel of the form carrier, the back and forth motion being imparted by mechanism for advancing said carriage with the form carrier, with the singeing elements located between two adjoining forms, and for causing the carriage to move in the opposite direction in a comparatively rapid singeing stroke, said mechanism being actuated in part by movement of the form carrier.
- 35 9. The method of singeing stockings, consisting in boarding each stocking on a comparatively flat form, moving the boarded stockings in one direction in the plane of said forms, and singeing each stocking by rapidly traversing spaced singeing elements past an interposed form, the said elements being moved with and in advance of a form bearing an unsinged stocking to a singeing station from which said elements are moved in the opposite direction for singeing said stocking.
- 40 10. The method of singeing stockings consisting in boarding each stocking, positioning the forms in a common plane and moving them in one direction therein, and singeing the stockings by passing singeing elements past the forms in the opposite direction.
- 45 11. The method of finishing stockings consisting in boarding the stockings on flat boarding elements, moving the boarded stockings on a continuously traveling endless carrier with the flat plane of each stocking form parallel with the direction of travel, and singeing the boarded stockings in succession by moving spaced singeing elements in an idle stroke with the stockings but out of singeing relation thereto and returning the elements in a working stroke so that the stockings pass between said elements and are thereby singed.
- 50 12. The method of singeing stockings which consists in moving the surface of the stockings to be singed in one direction and simultaneously moving the singeing member to apply singeing heat progressively in the opposite direction.
- 55 13. In an apparatus for finishing stockings, the combination with a traveling carrier and stocking forms mounted thereon in spaced relation, of a singeing device arranged adjacent said forms to be given a singeing stroke past the same, spring means normally urging said device in one direction for the singeing stroke, means for moving said device against the action of said spring means in the opposite direction on the idle strokes, and means for damping the spring-propelled strokes of said device for the singeing operations.
- 60 14. In an apparatus for finishing stockings, the combination with a traveling carrier and stocking forms mounted thereon in spaced relation, of a singeing device arranged adjacent said forms to be given a singeing stroke past the same, spring means normally urging said device in one direction for the singeing strokes, means for moving said device against the action of said spring means in the opposite direction on the idle strokes, and means for damping the spring-propelled strokes of said device for the singeing operations, said damping means comprising telescoping tubular members enclosing said spring means and providing a dash-pot cushioning action.
- 65 15. Apparatus of the character described

comprising, in combination, a carrier, means for actuating the same, a plurality of stocking forms carried by the carrier and moving therewith, a singeing device movable back and forth in a plane parallel to the path of movement of the forms, and means for producing the back and forth movements comprising connections for moving the device through an idle stroke with the carrier, and 10 a spring for moving the device in the opposite direction past the forms in its singeing stroke.

16. Apparatus of the character described comprising, in combination, a track, a carrier mounted to travel thereon, means for actuating the carrier, a plurality of stocking forms attached to the carrier at spaced

intervals, a singeing device having singeing elements in spaced relation between which the stocking forms are adapted to pass and 20 movable back and forth adjacent the path of movement of the forms, and means for producing the back and forth movements comprising a spring for moving the singeing device in the singeing stroke in the opposite direction to that of the forms, and 25 automatic devices for connecting the singeing device to the carrier, to cause the carrier to move the singeing device in the direction of movement of the forms and to store 30 energy in the spring, the automatic devices then disconnecting the singeing device from the carrier to permit the spring to act.

EDWARD J. ZICK.
